UNITED STATES PATENT OFFICE.

ALBERT MADÖRIN, OF QUARTEN, SWITZERLAND.

FISHING BOAT.

1,414,429.

Specification of Letters Patent. Patented May 2, 1922.

Application filed June 22, 1921. Serial No. 479,555.

To all whom it may concern:

Be it known that I, ALBERT MADÖRIN, a citizen of the Swiss Confederation, residing at Quarten, Canton St. Gall, Switzerland, have invented new and useful Improvements in Fishing Boats, (for which I have filed applications in Germany Feb. 28, 1921, and in Switzerland July 9, 1920,) of which the following is a specification.

10 The present invention relates to a new and improved fishing boat.

One object of the invention is to provide means to facilitate the drawing-in of the nets used for fishing purposes in such a manner that less labor is necessary, one man being only necessary to do the work of two men. Another object of the invention consists in the provision of a device which reduces friction of the net on the walls and 20 edges of the boat when the net is drawn into the boat preventing thereby rapid wearing and tearing of the net.

Other objects of the invention relate to the provision of minor parts cooperating 25 with the elements above noted and to details of construction, all of which will be more clearly set forth in the following specification:

With the above objects in view the invention resides in the parts and combination of 30 parts hereinafter described, and particularly set forth in the claim appended hereto.

In the drawings one mode of construction is shown by way of an example.

35 Fig. 1 shows an intermediate bearing in sectional elevation on line A—B Fig. 2.

Fig. 2 is a side elevation of the intermediate bearing.

Fig. 3 illustrates an end bearing with part 40 of a roller in section.

Fig. 4 is a side view thereof.

Fig. 5 shows a fishing boat fitted with the said rollers.

The fishing boat illustrated comprises on the upper edge of each side wall 8 a number 45 of tubular rollers 1 rotatably mounted in bearings 3, 5. The bearings 3 which are arranged between two adjacent rollers 1 are provided each with a flap 9 passing over the edge of the wall into the boat and with a 50 nose 4 arranged on the outer side of the wall 8. Each end of a roller is mounted on a ball 2 rotatably arranged on a bolt 7 screwed into the bearing 3. The end of each roller 1 projects into a recess 6 of the bearing 3 having some play in it. The bearings 5 are used to hold the free end of the last roller 1 of a row. The bearing 5 is provided with but one ball 2 and it is provided with a flap 10 fixed to the outside of the boat wall. 60 The balls 2 are secured against axial displacement by springy rings 11 engaging a groove in the bolt 7. The rollers 1 are arranged with reference to the edge of the boat wall in such a manner that the nets 65 drawn into the boat by the fisherman do not come into contact with the boat wall hence no friction is created which would damage the net. The rollers 1 running freely facilitate the work of drawing in the nets. As 70 the rollers 1 project into recesses 6 the net cannot become entangled between bearing and rollers.

What I wish to secure by Letters Patent is: 75 In combination, a member having a recess in one side and also having means whereby said member may be attached to a gunwale, a tubular roller arranged with one end in said recess, a bearing ball in said end of the roller and a supporting member for said bearing ball and on which the same rotates, said supporting member being attached to and projecting from the first-named member.

In witness whereof I affix my signature.

ALBERT MADORIN.
